UNITED STATES PATENT OFFICE.

HOWARD PARKER, OF BERLIN, NEW HAMPSHIRE, ASSIGNOR TO BROWN COMPANY,
OF BERLIN, NEW HAMPSHIRE, A CORPORATION OF MAINE.

METHOD OF AND APPARATUS FOR MOLDING REDUCERS FOR FIBROUS CONDUITS.

Application filed June 11, 1925. Serial No. 36,433.

This invention relates to reducers for conduits, and more particularly to tapered reducers made of fibrous material for use in connection with conduits or tubes of the same material. Such tubes or conduits are usually produced by winding paper or wood pulp on a mandrel, then removing the pulp from the mandrel in the form of a wet or "green tube", and thoroughly drying it. When used as a conduit for electrical wiring, or as a water pipe, the fibrous walls of the tubes are thoroughly waterproofed as by impregnating or saturating them with pitch or other suitable material.

15 The primary object of this invention is to provide a method and apparatus for the production of tapered reducers for use in connection with fibrous conduits in an expedient manner. Briefly stated, this object is attained by placing the desired length of green tube on a form having the desired reducing taper, and while maintaining it in a pulpy condition, pressing and shaping it to the form. The invention, including other objects 20 and advantages incident thereto, will best be understood from the following description thereof, when taken in conjunction with the accompanying drawings, in which

25 Figure 1 is a sectional view through the apparatus in a position to receive a green tube.

Figure 2 shows a similar view with the apparatus in a position to mold or shape a tube.

30 Figure 3 represents a plan view of the apparatus.

Referring to the drawings, the forming or molding apparatus may be considered as consisting of a lower and upper half,—the lower 35 half, generally speaking, constituting the form, and the upper half the former. The form consists of a frustro-conical hollow member 3 having a plurality of holes or perforations 2, regularly distributed over its sides and which communicate with its hollow interior. The form is provided at its lower end with an annular ledge or step 4 for supporting the green tube undergoing the shaping or molding treatment. Below the ledge 40 45 it is provided with a circular flange 5 serving as a support for the upper half of the apparatus and having lugs 6 protruding from its sides. The form rests on a base which is complementary to its lower portion. The base

comprises a frustro-conical portion 8, serving 55 as a bottom for the form 3 and making a good, tight fit with the lower interior sides of the form below the perforations 2, and a flanged portion 10 with lugs 12 at its sides, mating the flange 5 and the lugs 6 of the form. The 60 form 3 and the base may be secured to a suitable table or foundation 14 by common fastening means, as by bolts 15 passed through the complementary lugs 6 and 12.

The upper or forming half of the apparatus comprises a cylindrical cover 20 fitting over the form and above the ledge 4, the interior side wall of which is lined with a tube or diaphragm 18 of soft expansible sheet rubber secured thereto near its upper and 70 lower ends, as by rubber cement. The lower end of the cover has a flanged portion 21 and carries a rubber ring 25 which seals the cover to the flange 5. The top of the cover is also provided with a rubber ring 26, which may 75 rest on the top of the form 3, and serve as a seal therebetween for a purpose hereinafter described. The diaphragm 18 may be deformed to assume the shape of the form, by introducing fluid under pressure between the 80 diaphragm and the interior side wall of the cover. In thus assuming the shape of the form, the diaphragm 18 presses the green tube 85 exteriorly uniformly along its length against the form, so that the tube assumes the shape of the tapered form. For the introduction of fluid between the diaphragm and the interior wall, a conduit 30 communicates with a hole 31 extending through a lower portion of the cover 20 outwardly of the diaphragm. This 90 conduit is connected to the horizontal end 32 of a three-branch connector 311, the vertical branch 33 of which is connected to a fluid supply line 34, and the other horizontal branch 35 to a fluid outlet line 36,—both lines 95 being provided respectively with valves, as with the plug valves 37 and 38. Any suitable fluid under pressure, such as water, may be introduced between the diaphragm 18 and the interior side wall of the cover through the supply line 30. The water introduced 100 may be discharged by closing the valve 37 and opening the valve 38, and is facilitated by establishing communication between the atmosphere and the space between the diaphragm and the side wall of the cover. Communication with the atmosphere is made 105 through a conduit 40 communicating with a

hole 41 extending through the upper portion of the cover 20 and provided with a plug valve 43. In order to open the valves 38 and 43 and close the valve 37 simultaneously, the stems of the valves are respectively provided with arms 45, 46, and 47, pivotally connected to links 48 and 49, an upward movement of the links 48 and 49 closing the valves 38 and 43 and opening the valve 37, thus causing the diaphragm 18 to be expanded, and a downward movement of the links closing the valve 37 and opening the valves 43 and 38, thus discharging the water and permitting the diaphragm 18 to assume cylindrical form.

15 It frequently occurs that the green tube is hard and unmoldable, so that provision must be made to put the tube in a formative or pulpos condition by the addition of water thereto before pressure is applied by the diaphragm 18 in the shaping or forming operation. For this purpose, the interior 1 of the form communicates through the bottom 8 with a conduit 16 connected to the vertical end 50 of a three-branch connector 51. The horizontal end 53 of the branch connector is connected with a conduit 55 supplied with either hot water or steam, and the other vertical end 56 is connected with an outlet conduit 58 for the discharge of the water or steam from the form 3 after the green tube has been sufficiently softened. The conduits 55 and 58 are provided respectively with suitable valves, as the plug valves 60 and 61. In order to operate these valves simultaneously, the stems of the valves 60 and 61 are pivotally connected by arms 62 and 63 to a link 64, a downward movement of the link closing the valve 61 and opening the valve 60, thus allowing steam or hot water under sufficient pressure to be introduced into the interior of the form, and an upward movement of the link closing the valve 60 and opening the valve 61, thus allowing the water or steam to be discharged from the interior 1 of the form 3. To facilitate a rapid discharge of the steam or hot water from the interior 1 of the form 3, after the tube has been sufficiently moistened and softened, the interior is opened to the atmosphere through an opening 70 extending through the top of the form 3 and communicating with a lateral opening 71 through the upper portion of the cover 20, to which is attached a conduit 73 valved as at 74 and communicating with the atmosphere. The valve 74 is closed simultaneously with or prior to the downward movement of the lever 64, to introduce moisture into the interior of the form, and is opened after the tube has been sufficiently softened for the forming operation, simultaneously with or after the upward movement of the lever 64, to facilitate rapid discharge of the moistening agent from the interior of the form. Rubber rings 25 and 26, respectively, at the top and lower ends of the cover serve as seals and prevent any hot water or steam

introduced into the interior of the form from escaping.

In operation, the former 20 is first raised to a position as shown in Figure 1, the conduits 37 and 38 being connected respectively to flexible hose connections 80 and 81, which allows the upward and downward movement of the former into and out of operative position over the form. Cheesecloth 85, which prevents the sticking of the tube to the form, and which aids in the removal of the tube from the form after the molding operation, is placed over the form, and the desired length of green conduit 87 is placed thereover, the lower end resting on the ledge 80. When a conduit 88 (as indicated by dotted lines) of somewhat smaller diameter than the diameter of the lower end of the mold is being treated, the lower portion thereof is expanded as the tube is pressed onto the form, and the remainder is formed subsequently by the former or upper half of the mold. If a conduit 87, however, is equal to or greater than the diameter of the base of the form 3, it is formed or molded in entirety by 90 the former,—that is, by the uniform pressure exerted on its exterior by the diaphragm 18, as will be described. The former is then lowered into the position shown in Figure 2, the lower end 21 resting on the flange 5 of the base portion of the form, and it is so secured. The arm 64 is lowered, steam or water being introduced through the valve 60 and pipe 16 into the interior 1 of the form, the steam or water passing through the perforations and 100 cheesecloth into the pulp conduit 87 and softening it or placing it in a more formative or pulpos condition. The harder the green conduit is, the longer it is subjected to the water or steam treatment. The tube, having 105 been sufficiently softened, is ready to be molded, and the moistening agent is allowed to flow out from the form through the pipe 16 by raising the arm 64,—the air valve in the pipe 73 also being opened to allow air at 110 atmospheric pressure to assist in the removal of the moistening agent from the form. The lever 48 is raised, the water under pressure passing through the conduit 30 and forcing the rubber diaphragm 18 around the tube 115 against the form, causing the tube to assume a tapered shape, and squeezing out any excess moisture therefrom through the perforations 3. The reducer now having been formed, the lever 48 is moved downwardly, the valves 43 and 38 being opened, and the valve 37 closed, thus allowing the water to escape through the pipe 30. The upper half of the mold is then raised to its inoperative position, and the operator grasps the upper edges of the cheesecloth and lifts the reducer from the mold.

The hereinbefore described method of molding reducers yields a product which is similar in characteristics to the conduits with which it is used; that is, the reducers are 130

strong and their constituent fibers are densely compacted and interfelted. Subsequent to the molding operation, the wet reducers may be dried and treated with a waterproofing compound, and they may be turned and their ends formed into any one of a variety of joints, by suitable instrumentalities.

Having thus described a preferred embodiment of this invention, it should be evident to those skilled in the art that it is susceptible of various changes and modifications without departing from its spirit or scope as defined by the appended claims.

What I claim is:

1. A method of producing a tapered fibrous article, which comprises placing a fibrous tube over a frusto-conical form, wetting said tube so as to soften it, applying pressure on the wall of said tube so that it assumes the shape of the form, removing the tapered tube from the form, and drying it.

2. Apparatus for forming fibrous reducers, comprising a hollow form over which a tubular fibrous conduit may be positioned and having perforations distributed over its sides communicating with its hollow interior; means for introducing moisture into the interior of said form for wetting and softening the fibrous conduit; means for discharging the moisture from the interior of said form; a cover adapted to be placed over said form; a flexible rubber diaphragm within the interior wall of said cover and secured thereto at its edges; and means for causing said diaphragm to expand so as to press the tube against the form.

3. Apparatus for forming fibrous reducers, comprising a form over which a tubular fibrous conduit may be positioned, a cover adapted to be placed over said form, an expandable rubber diaphragm covering the interior wall of said cover and secured thereto at its edges, and means for causing said diaphragm to expand and press the tube against the form.

4. Apparatus for producing tapered reducers, comprising a form over which a fibrous tube may be positioned, means for wetting the tube so as to render it somewhat soft and pulpos, and means for applying a uniform pressure to the wall of said tube while it is soft, in a manner such that it assumes the shape of the form.

5. Apparatus for producing tapered reducers, comprising a form over which a fibrous tube may be positioned, a cover fitting over said form, a flexible rubber diaphragm overlying the interior wall of said cover, and means for introducing fluid between the wall of said cover and the diaphragm whereby said diaphragm expands and uniformly presses said tube against said form.

6. A mold for forming tapered reducers, comprising a hollow form over which a tubu-

lar fibrous conduit may be positioned and having a plurality of perforations distributed over its sides communicating with its interior; means for introducing moisture into the interior of said form; means for discharging the same from the interior of said form; a cover for said form provided with an expandable diaphragm secured at its edges thereto, and normally resting against its interior wall; means for introducing fluid between the wall of said cover and said diaphragm to cause the deformation of the latter against the form, whereby the wet conduit assumes the shape of said form; and means for discharging said fluid to allow said diaphragm to contract and assume its normal condition.

7. A mold for forming tapered reducers, comprising a hollow form over which a tubular fibrous conduit may be positioned and having a plurality of perforations distributed over its sides, communicating with its interior; a conduit communicating with the interior of said form; moisture inlet and moisture outlet pipes connected to said conduit; means for opening the inlet pipe while closing the outlet pipe and opening the outlet pipe while closing the inlet pipe, means for establishing communication between the interior of said form and the atmosphere for facilitating the discharge of moisture from the form, a cover for said form provided with an expandable rubber diaphragm secured at its edges thereto and normally resting against its interior wall; means for introducing fluid between said cover and said rubber diaphragm to cause the expansion of the latter against the form, whereby the tube assumes the shape of said form, and means for discharging said fluid to allow said diaphragm to contract against said cover.

8. A mold for forming tapered reducers, comprising a hollow form over which a tubular fibrous conduit may be positioned and having a plurality of perforations distributed over its sides communicating with its interior, a conduit communicating with the hollow interior portion of said form, moisture inlet and moisture outlet pipes connected to said conduit; means for opening the inlet pipe while closing the outlet pipe and opening the outlet pipe while closing the inlet pipe; means for establishing communication between the interior of said form and the atmosphere for facilitating the discharge of moisture from the form, a cover for said form provided with a flexible rubber diaphragm secured at its edges thereto and normally resting against its interior wall, a conduit extending through the lower end of said cover to said rubber diaphragm, fluid inlet and fluid outlet pipes connected to said conduit, a pipe communicating with the atmosphere extending through the cover to the rubber diaphragm; and means for opening the fluid inlet pipe while closing the air and fluid outlet pipes to cause the expan-

sion of the tube against the form, and for opening the air and fluid outlet pipes while closing the fluid inlet pipe to cause the discharge of the fluid and the contraction of the rubber tube.

9. A mold for forming tapered reducers, comprising a hollow form over which a tubular fibrous conduit may be positioned, and having a plurality of perforations distributed over its sides communicating with its interior; means for introducing moisture into the interior of said form; means for discharging the same from the interior of said form; a cylindrical cover for said form, provided with a flexible rubber diaphragm secured thereto at its edges and normally resting against its interior wall; a conduit extending through the lower end of said cover to said rubber diaphragm; fluid inlet and fluid outlet pipes connected to said conduit; an air pipe communicating with the atmosphere, extending through the cover to the rubber diaphragm; and means for opening the fluid inlet pipe while closing the air and fluid outlet pipes to cause the expansion of the tube against the

form, and for opening the air and fluid outlet pipes while closing the fluid inlet pipe to cause the discharge of the fluid and the contraction of the rubber diaphragm.

10. A method which comprises winding a web of pulp on itself into cylindrical tubular form, deforming the tube while wet into tapered form, and drying the tapered tube.

11. A method which comprises winding a web of pulp on itself into cylindrical tubular form, placing the tube while wet over a frusto-conical form, pressing the tube against the form, removing the tapered tube thus produced from the form, and drying it.

12. A method which comprises winding a web of pulp on itself into cylindrical tubular form, applying a substantially uniform pressure on the wall of the tube to cause the tube to be crowded inwardly against the form, removing the tapered tube thus produced from the form, drying it, and impregnating it with waterproofing material.

In testimony whereof I have affixed my signature.

HOWARD PARKER.
